UNITED STATES PATENT OFFICE.

LYNN G. RILEY, OF WILKINSBURG, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

Application filed January 6, 1921. Serial No. 435,304.

To all whom it may concern:

Be it known that I, LYNN G. RILEY, a citizen of the United States, and a resident of Wilkinsburg, in the county of Allegheny and State of Pennsylvania, have invented a new and useful Improvement in Systems of Control, of which the following is a specification.

My invention relates to motor-control systems and it has particular relation to such systems as are employed in connection with railway cars.

The object of my invention is to provide a simple and efficient means for penalizing the operator in case the master controller is actuated too rapidly, which may result in excessive current in the motor circuit, as well as discomfort to the passengers.

Various mechanical retarding devices for controllers are in use but these are not wholly satisfactory. Electrical devices dependent upon values of current or voltage in the motor circuit are, in general, unsatisfactory, since they do not function properly under varying load conditions. In the present system, it is proposed to use a simple master controller, having a drum development of novel form, in conjunction with any standard railway control equipment.

The single figure of the accompanying drawing, illustrates, diagrammatically, a system embodying my invention.

A motor, having an armature 1 which is connected through a contactor 2 to a positive line conductor 3, has a series field magnet winding 4. A resistor 5, which is in circuit with the armature, is connected to a negative line conductor 6.

A master controller 7 is provided with a plurality of contact members of which members 8, 9 and 10 engage mutually in the first operative position *a* of the master controller. Contact members 14, 15 and 16 engage in positions *a*, *c* and *e* of the master controller and, in positions *b* and *d*, contact members 14, 15 and 21 are in engagement and member 16 is disengaged. Contact member 21 is disengaged in positions *a*, *c* and *e*.

A relay 19, in conjunction with the master controller 7, controls the line contactor 2. Contactors 24 and 25 control the accelerating resistor 5 in the usual manner.

A master controller 7, when actuated to its first operative position *a*, establishes a circuit for line contactor 2, extending from

positive line conductor 3, through master switch contact member 8, contact segment 9, contact member 10, conductor 11, and coil 12, to the negative line conductor 6.

A main circuit for the motor is established from the positive line conductor 3, through line contactor 2, series field-magnet winding 4, motor armature 1 and accelerating resistor 5, to the negative line conductor 6.

When the contactor 2 closes, a holding circuit, which is established for its actuating coil 12, extends from the positive line conductor 3, through conductor 13, contact member 14, contact segment 15, contact member 16, conductor 17, interlock member 18 and coil 12, to the negative line conductor 6.

In actuating the master controller to its second operative position *c*, it passes through an intermediate position which may be represented by *b*.

When the master controller leaves position *a* and moves toward position *c*, contact finger 21 engages contact segment 15, and a circuit is established for relay coil 22 extending from the positive line conductor 3, through conductor 13, contact member 14, contact segment 15, contact member 21 and coil 22, to the negative line conductor 6. Relay 19 is, therefore, actuated to establish a circuit for actuating coil 12 of contactor 2, extending from the positive line conductor 3, through conductor 23, relay 19, conductor 17, interlock 18 and coil 12, to the negative line conductor 6.

In establishing position *b*, the contact segment 15 is disengaged from contact member 16, thereby opening the holding circuit of coil 12. The initial circuit of coil 12 is also broken when contact segment 9 is disengaged from contact members 8 and 10.

When the controller approaches position *c*, contact finger 16 again engages contact segment 15 to again complete the initial holding circuit for actuating coil 12. Slightly further in the movement of the controller, the contact finger 21 engages an insulating member 26 to open the circuit of relay coil 22. If the controller has been actuated at normal speed, the contactor 2 remains closed.

If the operator actuates the master controller from position *a* to position *c* with sufficient rapidity, contact member 21 engages the insulation member 26 to open the circuit of coil 22 before the relay 19 has

closed. Therefore, line contactor 2 will open and, in order to re-establish the motor circuit, it will be necessary for the operator to return the master controller to position *a* to re-establish the engagement of contact segment 9 with contact members 8 and 10 and a circuit through coil 12, as previously traced.

In order not to be so penalized, the operator will naturally actuate the master controller from point to point at a rate not to exceed that predetermined by the time elements inherent in the co-operating elements. It will be noted that relay 19 is inoperative in positions *a*, *c* and *e*, which positions represent operative points of the master controller. The drum segment 15 is designed with sufficient insulation distance between points *a* and *c* to insure the interruption of a circuit comprising coil 12 and contact member 16.

When the master controller is actuated from position *c* to position *e*, the sequence of control is similar to that described in passing from *a* to *c*.

The accelerating resistor 5 is shunted by contactors 24 and 25 in any well-known manner, contactor 24 being operative in position *c* and contactor 25 in position *e* of the master controller.

It is evident from the foregoing disclosure that the system employed is extremely simple and that it avoids the necessity for the use of easily deranged devices. It is desirable, particularly in railway control systems, that a fairly constant rate of acceleration be employed. It is very objectionable to accelerate much more rapidly with light loads than with heavy ones and, in my invention, the maximum rate of acceleration is determined, while there is no fixed minimum rate.

I claim as my invention:

1. The combination with a motor and a controller, of means independent of said motor circuit for interrupting said circuit when the actuation of said controller exceeds a predetermined rate.

2. The combination with a motor and a controller, of means comprising a relay for interrupting said motor circuit independently of said motor circuit when the actuation of said controller exceeds a predetermined rate.

3. The combination with a motor and a line switch, of a controller and means controlled by said controller, when actuated at a predetermined rate, for controlling said

line switch independently of said motor circuit.

4. The combination with a motor and a line switch, of a controller, and means comprising a relay controlled by said controller, when actuated at a predetermined rate, for controlling said line switch independently of said motor circuit. 65

5. The combination with a motor and a controller, of means independent of said motor circuit for maintaining said circuit while the controller is actuated at less than a predetermined rate. 70

6. The combination with a motor and a controller, of a line switch, controller contact members for controlling a circuit for the coil of the line switch, an interlock actuated by said line switch for maintaining said coil circuit independently of said contact members, means comprising said contact members for interrupting the circuit of said coil, and a relay actuated independently of said motor circuit for preventing the interruption of said coil circuit. 75 80

7. The combination with a motor and a controller, of a line switch, controller contact members for controlling a circuit for the coil of the line switch, an interlock actuated by said line switch for maintaining said coil circuit independently of said contact members, means for interrupting the circuit of said coil comprising said contact members, and a relay actuated independently of said motor circuit for preventing the interruption of said coil circuit while the controller is actuated at less than a predetermined rate. 85 90

8. The combination with a motor and a controller having a plurality of operative positions, of a line contactor, an interlock actuated by the line contactor, a relay actuated by said controller for coacting with said interlock to maintain a circuit through the coil of said contactor, contact members operative in one position of said controller to actuate said contactor independently of said relay and said interlock, and contact members, operative in other positions of said controller, for coacting with said relay and said interlock to control said line contactor in accordance with the rate at which said controller is actuated. 95 100 105

In testimony whereof, I have hereunto subscribed my name this 22nd day of December, 1920.

LYNN G. RILEY.
